DESIGN FOR A PHOTOGRAPHIC ENLARGER

Philip Sinetar, Long Beach, N. Y.

Application August 1, 1946, Serial No. 132,190

Term of patent 14 years

(Cl. D61—1)

To all whom it may concern:

Be it known that I, Philip Sinetar, a citizen of the United States, residing in Long Beach, L. I., county of Nassau, State of New York, have invented a new, original, and ornamental Design for a Photographic Enlarger, of which the following is a specification, reference being had to the accompanying drawing, forming a part thereof, in which:

Fig. 1 is a perspective view of a photographic enlarger, showing my new design;

Fig. 2 is a rear perspective view of the same, and

Fig. 3 is a top plan view.

I claim:

The ornamental design for a photographic enlarger, as shown.

PHILIP SINETAR.
